POOL WITH INTEGRAL SLIDE

Leonard E. Greenberg, West Hartford, and Joseph Diemand, Simsbury, Conn., assignors to Coleco Industries, Inc., Hartford, Conn., a corporation of Connecticut

Filed Apr. 4, 1969, Ser. No. 16,581

Term of patent 14 years

Int. Cl. D21—3

U.S. Cl. D34—5

FIG. 1

FIG. 2

FIG. 3

FIG. 4

FIG. 5

FIGURE 1 is a perspective view of a pool with an integral slide showing our design;

FIGURE 2 is a plan view thereof to an enlarged scale;

FIGURE 3 is a side elevational view thereof on the same scale as FIGURE 2;

FIGURE 4 is an end elevational view thereof on the same scale as FIGURE 2; and

FIGURE 5 is a fragmentary sectional view thereof along the line 5-5 of FIGURE 2 and to a still further enlarged scale.

We claim:

The ornamental design for a pool with integral slide, as shown.
